FOREIGN PATENT DOCUMENTS

JP D1731918 * 2/2012

Primary Examiner — George D. Kirschbaum*Assistant Examiner* — Antoinette Martine Suiter(74) *Attorney, Agent, or Firm* — Studebaker & Brackett PC(57) **CLAIM**

The ornamental design for an object detection device, as shown and described.

DESCRIPTION

FIG. 1 is a first perspective view of front, right and top sides of an object detection device showing our new design; FIG. 2 is a second perspective view of front, left and bottom sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the usage state.

The broken lines shown in the FIGS. 1 to 8 are included for the purpose of illustrating portions of the object detection device that form no part of the claimed design.

The broken lines shown in the FIG. 9 represent environmental subject matter and form no part of the claimed design.
